SELECTIVE INDICIA PRODUCTION

Lester E. Haining, Audubon, N.J., assignor to Radio Corporation of America, a corporation of Delaware

Application May 3, 1954, Serial No. 427,238

9 Claims. (Cl. 340—324)

This invention relates to novel methods of and apparatus for selectively producing characters or indicia by electronic means, and more particularly to novel methods of and apparatus for producing indicia or characters on the face of a kinescope.

In an electronic printing process letters, numbers and other symbols may be produced on the face of a kinescope. These letters, numbers or other symbols, which may be termed indicia or characters, may be permanently recorded from the kinescope face by any light sensitive process such as photography. These electronic printing processes may be operated at extremely high speeds. They are particularly well adapted to recording coded information produced by electronic computers.

Some of the problems encountered in processes of this type are the need for improvement of reproduction contrast, and the need for developing efficient systems which may use relatively lower precision components. This invention teaches how such indicia may be reproduced utilizing, in most respects, inexpensive standard components, and which develops high contrast recorded information at a high light efficiency.

An object of this invention is to provide a novel method of and apparatus for producing indicia on a kinescope face in response to a coded input signal.

Another object is to provide a novel method of and apparatus for producing indicia or figures on a kinescope which utilizes standard or relatively low precision components.

A further object is to provide a novel method and apparatus of the aforementioned type for producing high contrast indicia on a kinescope face.

One application of the invention is in high speed printing where the symbols are formed on the face of a kinescope and from which they can be printed off by a photographic process. The apparatus to be described is for the purpose of forming such symbols and makes available a full alphabet and set of numerals with a reasonably small amount of equipment. Other symbols or pictorial figures may be formed. Code controlled selection of a desired symbol is disclosed.

The present invention utilizes patterns having predetermined outlines or shapes to provide a series of successive line elements. Each of the line elements represents or is related to a plane coordinate of a point on a pre-selected plane figure. Means are provided to derive a successive series of signals corresponding to coordinates of successive points on the figure. The shape of the pattern, therefore, characteristically modulates these successive signals. These signals may be applied to deflect the beam of a recording kinescope in a series of successive points which trace out the preselected figure, letter or indicia.

Other objects and advantages of the present invention will become apparent to one skilled in the art from a reading of the following specification in conjunction with the accompanying drawings of an illustrative example con-

2

structed according to the teachings of the present invention in which:

Fig. 1 is a schematic diagram of an embodiment of this invention;

5 Figs. 2 and 3 illustrate more in detail the mask or charts shown in Fig. 1 and a method by which they may be scanned;

Fig. 4 is a diagram illustrating coordinates of deflection derived in scanning successive line elements of patterns

10 representing the letter "B," for example; and

Fig. 5 is a diagram of a modification of the embodiment shown in Fig. 1.

In Fig. 1 a schematic diagram is shown of the various components in their respective positions connected to produce indicia on the reproducing or recording kinescope face according to the teachings of this invention.

A code input device 10 is connected to provide a signal to vertical beam position selecting devices 12 and 13 and horizontal beam position selecting devices 14 and 15.

20 The code input device may, for example, be a perforated tape reading apparatus of the type shown in McNaney Patent 2,283,383 granted May 19, 1942. The vertical position selectors 12 and 13 and the horizontal position

25 selectors 14 and 15 may also, for example, be similar to the beam positioning apparatus shown in McNaney Patent 2,283,383. These position selectors provide signals for selectively positioning the beams of the generating and reproducing cathode ray tubes respectively (to be later described) at preselected positions determined by the horizontal and vertical deflection signals applied. Only so

30 much of the McNaney system may be used as is necessary to position the kinescope beams at preselected points.

The vertical and horizontal positioning selectors 12 and 14 may be connected, respectively, jointly to the vertical and jointly to the horizontal deflection plates of generating cathode ray tubes 16 and 18. The selectors 13 and 15 are connected, respectively, to the deflection plates of reproducing kinescope 20. Electrostatic deflection plates, which are by now well known, are shown conventionally on the drawing, but it will be understood that electromagnetic deflection means may be employed. The connections to the respective cathode ray tubes may be made through vertical and horizontal mixers 22 and 24 to the generating kinescopes. The selectors 13 and 15 may be respectively connected to the reproducing or recording kinescope through vertical mixer 26 and horizontal mixer 28.

40 A radio frequency source 30 of any well known type, such as an oscillator or a multivibrator, may be connected to the vertical positioning mixer 22 supplying the vertical deflection plates of generating cathode ray tubes 16 and 18. A sawtooth wave generator 32 of any type well known in the art may be connected to the horizontal positioning mixer 24 of the generating cathode ray tubes 16

45 and 18. A blanking device 34 may be connected in the line from code input device 10 to the electron guns of cathode ray tubes 16, 18 and 20 to keep the beams cut off until a code signal to reproduce a character arrives. The sawtooth wave generator 32 is connected to the blanking device 34 to blank the beams on the return trace.

50 Photosensitive pickups 36 and 38 may be disposed in the path of light produced on the fluorescent face of the generating cathode ray tubes 16 and 18 respectively. A mask 40 is positioned between the face of cathode ray tube 16 and its associated photosensitive pickup 36. The mask 40 includes an array of patterns which provide line elements which are related to or represent horizontal coordinates of successive points on a number of figures or indicia. Mask 42 is disposed between the face of cathode ray 18 and its associated photosensitive pickup 38.

The mask 42 includes an array of patterns which provide line elements which are related to or represent vertical coordinates of successive points on the same figures or indicia. The masks may be cutout in the shape of these patterns to allow predetermined amounts of light to pass to these photosensitive pickups according to the magnitude of these line elements. The structure of these masks will be described in detail in the discussion relating to Fig. 2.

Light concentrating lenses 44 and 48 are interposed between the respective masks and photosensitive pickups to concentrate the light passing through the mask on the photosensitive pickup. The signals derived from photosensitive devices 36 and 38 are respectively passed through amplifiers 50 and 52 to the respective horizontal and vertical mixers 28 and 26 of reproducing kinescope 20.

In Figs. 2 and 3 are shown a detailed representation of masks 40 and 42 which are shown in their operating positions in Fig. 1. The masks may be subdivided into a predetermined number of areas or blocks. Each mask may include a cutout of a predetermined shape to provide successive line elements for respectively generating a vertical and horizontal sweep deflection signal for the reproducing kinescope. Each cutout, therefore, has a characteristic shape corresponding to a preselected character or indicia.

The charts or masks 40 and 42 are divided into thirty-six regions or blocks arranged in three vertical columns of twelve blocks each. Patterns, which may be in the form of cutouts, are provided within each block. The cutouts 41, 43 and 45, for example, may be arranged in blocks in mask 40 to provide line elements for representing horizontal coordinates of points on the letters A, B, and C respectively. Cutouts 51, 53, and 55 may be arranged in blocks on mask 42 to provide line elements for representing vertical coordinates on the letters A, B and C respectively. A complete alphabet and set of numbers or any set of plane figures may be provided by properly shaping the patterns.

To represent the letter "B", for example, the cutouts may be shaped as shown in 43 and 53 in Fig. 4. The illustrative line elements indicated by reference characters 1 to 7 represent the respective vertical and horizontal coordinates of illustrative points 1a to 7a shown on the trace 57 of letter "B".

When the beams of the horizontal and vertical sweep generating cathode ray tubes 16, 18 are positioned to traverse the cutouts corresponding to the preselected character simultaneously in the horizontal mask 40 and the vertical mask 42, sweep deflection signals will be developed through the photosensitive devices to cause the electron beam of reproducing kinescope 20 to trace out the preselected indicia on its face.

The device operates in the following manner to produce preselected characters or indicia on the face of the reproducing kinescope. The code input device 10 may read a coded input, for example, a perforated tape (not shown) to provide positioning signals to the position selecting devices 12 and 14 of the generating cathode ray tubes and 13 and 15 of the reproducing kinescope. Each row of perforations on the tape (not shown) may provide a signal corresponding to a vertical and horizontal coordinate of selective beam deflection. These coordinate signals position the cathode ray beams at predetermined blocks on the masks to generate vertical and horizontal sweep deflections, and separate signals may also position the beam of the recording kinescope 20 at a predetermined starting point. These sweep deflection signals are applied to the deflection plates of the reproducing kinescope to cause its electron beam to trace out the preselected character.

The beams of the generating and recording cathode ray tubes are maintained turned off by the blanking device 34 until a signal is received from the code input device 10 to turn the beam on. The blanking device 75

may be arranged by means well known in the art to turn the beams on only when the code input device is reading the perforations corresponding to a preselected character on the tape. The blanking device simultaneously turns on the beams of all the cathode ray tubes at the same time to generate the vertical and horizontal sweep deflection signals corresponding to the preselected character and to simultaneously apply the sweep deflection signals to the reproducing kinescopes through photosensitive pickup devices 36 and 38 and amplifiers 50 and 52.

When the beams are turned on, the generating beams scan the preselected cutouts to generate vertical and horizontal sweep deflection signals to be applied to the deflection plates of the recording kinescope to cause its beam 10 to trace out the preselected character on its face. The character may be started at a preselected position on the kinescope 20 face determined by the signals derived from the code input source 10 through the vertical and horizontal position selectors 13 and 15 and vertical and horizontal mixers 26 and 28.

The electron beams of the generating kinescopes are moved by the predetermined horizontal and vertical deflection positioning signals to pick out or select the respective mask cutouts corresponding to the preselected character. The radio frequency source 30 provides a signal to the vertical mixer 22 for causing the electron beam to move rapidly vertically up and down. This provides a vertical line passing up and down across the preselected cutout. The sawtooth wave generator 32, connected to horizontal mixer 24, provides a means for traversing the vertically scanned lines across the preselected cutout. The beams in the character generating cathode ray tubes are therefore progressively moved simultaneously across their respective cutouts in an approximately linear fashion. The successive elements of light which pass through the mask, therefore, may be regulated or modulated by varying the shape of the cutout in the direction of the beam movement. The vertical and horizontal deflection signals to trace out the preselected character on the recording kinescope face are, therefore, controlled or modulated by the shape of the cutout. The preselected character is traced out during the time that it takes the generating beams to traverse the preselected cutout. The light which passes through the mask to energize the photocells is, therefore, instantaneously proportional to the vertical and horizontal signals required to deflect the recording kinescope beam in a trace which corresponds to the shape of the preselected character.

The equipment described as being assembled in novel combinations is standard in nature and need not be of prohibitively high quality. The generating cathode ray tubes need not be high precision tubes. They may be the electrostatically deflected type. They may be, for example, the type which is ordinarily used in oscilloscopes. The recording kinescope may be any well known kinescope type.

The masks, for example, may be provided with cutouts for producing a complete alphabet and a complete set of numbers. The use of these masks does not impose excessive linearity requirements upon the other components of the system. Various masks may be provided for upper or lower case letters, script or other types of symbols. If the tubes are of relatively higher quality and operate more precisely, a great many more symbols can be produced.

In Figs. 2 and 3 are shown, the masks required to generate or modulate, respectively, the horizontal and vertical sweep deflection signals to be applied to deflect the beam of the recording kinescope to trace out the letter B (shown in Fig. 4). The vertically moving beam traces out a succession of line elements 1 to 7 across the cutout as shown. The illustrative line elements 1 to 7 are shown linked to the corresponding points 1a to 7a of the letter "B" which is traced out by the successive

signals generated while the beam is traversing these line elements. The cutouts may be used to generate the character B, as shown, provided that the circuit constants are linear. This would be accomplished if the sweep across the cutouts is linear, and if the deflection applied to the recording kinescope beam is precisely proportional to the light passed through the cutout. If a magnetically deflected recording kinescope with inductive effects in its yoke were used, departures from linearity in these conditions could possibly cause distortion unless known compensating circuits are employed or unless yoke design compensates for non-linearity in a known manner. The inductive effect can be compensated for in accordance with this invention simply by trimming the cutouts to make the resultant beam deflection trace out the precise form of the preselected character regardless of any individual distorting effects present in the components of the system. In this way, errors inherent in individual components can be balanced out against one another without complication of apparatus.

The accuracy of positioning the beam at the proper point to start traversing each cutout need not be particularly high. The precision of the scanning or beam traversing signals provided by the radio frequency source 30 and the sawtooth generator 32 also need not be high. This invention requires only that the beam travel completely across each pattern. The beam travel may, therefore, overlap the individual patterns an appreciable amount. This amount is limited only by the size of the mask and the quantity and size of the patterns which determines the spacing between individual cutouts. Since this spacing may be relatively great, the position of the scanning beam may be, therefore, displaced considerable amounts without distorting the deflection signals applied to the recording kinescope.

Another favorable aspect inherent in this invention is that the beam in the reproducing or final display tube is maintained turned on during all the time that the character symbol or indicia is being traced out on its face. In scanning systems of the television type, the beam is turned on only when it arrives at the position on a horizontal line where a segment or element of an object is to be reproduced. This invention, therefore, provides a relatively high light efficiency or contrast between the symbol and background in the final display.

Since the information passed in a system constructed according to this invention is less complex than in the normal type of television scanning and reproducing system, the frequency range used by this equipment may be less, and the band pass of the components such as the amplifiers may be lower. This permits the use of less precise and less expensive amplifiers.

In Fig. 5, is shown a modification of this invention in which a more elaborate optical system is used to allow only one generating kinescope to be used for generating both the horizontal and vertical sweep deflection signals. The light passing from the face of a generating cathode ray tube 60 may be passed through a lens 62 to strike a beam splitting mirror 64. The beam splitting mirror, for example, may be of the half-silvered type. A portion of the light passes through the mask 40a and strikes the light converging lens 66. The mask 40a may be arranged in a similar manner to mask 40 as shown. This light may be concentrated on a photosensitive device 68 which may be connected to the horizontal deflection circuit of the recording kinescope 20 in a similar manner to the connection of photosensitive device 38 in Fig. 1.

The beam splitting mirror from its surface reflects the other portion of the light through another mask 42a. The mask 42a may be arranged in a similar manner to mask 42 as shown. The light is converged by condensing lens 72 to strike the photosensitive pickup 74 which may be connected in the vertical sweep deflection circuit of the recording kinescope 20. In this way, the light from a single cathode ray tube may be divided by a beam split-

ting mirror and focussed on the two masks which have patterns which provide successive line elements to modulate the light passing through to generate the vertical and horizontal sweep deflection signals to provide coordinate deflection for the beam in a reproducing kinescope. The preselected character is traced out on the kinescope face by these coordinate deflection signals in the manner previously described.

10 The optical links may be eliminated by using monoscopes having signal plates instead of using cathode ray tubes and masks to generate or modulate the sweep deflection signal. The signal plates of the monoscope may be constructed to have contrasting secondary emissive patterns similar in shape to the mask cutouts. Two monoscopes may be required, one for the horizontal sweep deflection signal and the other for the vertical sweep deflection signal.

What is claimed is:

1. A system for producing preselected indicia on the 20 face of a kinescope in response to a coded signal from an input source comprising storage means providing an array of patterns of predetermined shapes respectively related to coordinates of points on said indicia for modulating sweep deflection signals characteristic of said preselected

25 indicia, means for providing a scanning electron beam for selectively scanning said patterns, selector means connected to said input source for selectively positioning said scanning electron beam to scan a preselected pattern, means for deriving a kinescope sweep deflection signal 30 characteristic of points on said preselected indicia in response to said modulation of said scanning beam, and means for applying said sweep deflection signal to said kinescope to cause said kinescope to trace out said preselected indicia on its face.

35 2. A system for producing preselected indicia on the face of a kinescope in response to a coded signal from an input source comprising storage means providing an array of cutouts of predetermined shape for modulating the passage of light, means providing a scanning electron beam for progressively passing light through said cutouts, 40 selector means connected to said input source for selectively positioning said scanning electron beam to progressively scan a preselected cutout, means for deriving a kinescope sweep deflection signal characteristic of said preselected indicia in response to the amount of light 45 passed through said cutout, and means for applying said sweep deflection signal to said kinescope to cause said kinescope to trace out said preselected indicia on its face.

3. An arrangement for producing preselected indicia 50 on the face of a kinescope in response to a coded signal from an input source comprising storage means providing a preselected array of cutouts of predetermined shapes related to coordinates of points on said indicia for modulating the passage of light, means for providing a scanning electron beam for progressively scanning an area 55 including one of said preselected cutouts to generate a light output, a beam position selecting means connected to said input source for selectively positioning said scanning electron beam to progressively scan across a preselected cutout, and a photosensitive signal generating 60 means disposed to receive light passed through said preselected cutout and connected to said kinescope for generating a deflecting signal in response to the modulation of light by said cutout to cause kinescope to trace out 65 said preselected indicia on its face.

4. An arrangement for producing preselected indicia at a preselected position on the face of a kinescope in 70 response to a coded signal from an input source comprising storage means providing an array of cutouts for modulating the passage of light, cathode ray tube means providing a scanning electron beam for progressively scanning an area covering one of said cutouts, said cathode ray tube means including a beam position selecting means connected to said input source for selectively positioning said scanning electron beam to progressively scan

across one of said preselected cutouts, a photosensitive signal generating means disposed to receive light passing through said preselected cutout and connected to said kinescope for generating a deflecting signal in response to the modulation of light by said cutout to cause said kinescope to trace out said preselected indicia on its face, and a kinescope beam position selecting means connected to said input source to selectively position said indicia at a preselected starting position on the face of said kinescope in response to said input signal.

5. An arrangement for producing preselected indicia on the face of a kinescope in response to a coded signal from an input source comprising storage means providing an array of cutouts having predetermined shapes related to coordinates of points on said indicia for modulating a scanning light beam, a cathode ray tube providing a light beam producing scanning electron beam for progressively scanning an area covering one of said cutouts, a cathode ray tube beam position selecting means connected to said input source for selectively positioning said scanning electron beam to progressively scan a light beam across one of said cutouts in response to said input signal, a photosensitive signal generating means disposed to receive light passing through said cutout and connected to said kinescope for generating a deflecting signal in response to the light passed by said cutout to cause said kinescope to trace out said preselected indicia on its face, and a means for turning on beam of said cathode ray tube means and said kinescope beam when said input signal is received.

6. An arrangement for producing preselected indicia on the face of a kinescope in response to a coded signal from an input source comprising an array of cutouts of predetermined shapes respectively related to coordinates of points on said indicia for modulating the passage of a scanning beam, a scanning cathode ray tube disposed for selectively scanning across one of said cutouts, beam position selector means connected to said input source for providing beam positioning deflections to said scanning cathode ray tube and said recording kinescope for posi-

tioning the scanning beam to traverse a preselected cutout and for positioning the kinescope beam to start its trace at a preselected location, means for generating a scanning pattern connected to said cathode ray tube, and a photosensitive signal generator disposed to receive the beam passed through said preselected cutout and connected to said recording kinescope to provide a signal to deflect said kinescope beam in a pattern which traces out said preselected indicia on its face.

10. The invention as set forth in claim 6 in combination with a blanking means connecting said cathode ray tube and said kinescope to said coded input device for maintaining said cathode ray tube beam and said kinescope beam cutoff until said coded input signal is received.

15. The invention as set forth in claim 6 wherein said scanning pattern generating means is comprised of a radio frequency source in combination with a sawtooth wave generating source.

20. The invention set forth in claim 6 wherein said scanned cutout is comprised of a pair of cutouts each having an associated photosensitive generator, said cutouts being in combination with a means for passing light from said scanning beam through each of said cutouts to generate a horizontal and vertical component of deflection for said kinescope beam.

25. The invention as set forth in claim 6 wherein said scanned cutout is comprised of a pair of cutouts each having an associated photosensitive generator, said cutouts being in combination with a means for passing light from said scanning beam through each of said cutouts to generate a horizontal and vertical component of deflection for said kinescope beam.
